CONTINUOUS FREEZING DEVICE

Harvey D. Geyer, Dayton, Ohio, assignor, by
mesne assignments, to General Motors Corpora-
tion, Detroit, Mich., a corporation of Dela-
ware

Application December 5, 1931, Serial No. 579,131

18 Claims. (CL 62—105)

This invention relates to an ice-freezing de-
vice having an endless flexible container belt
wherein water is frozen and the ice blocks are
later ejected by the passage of the belt over
5 a roller or other curved surface.

An object of the invention is to provide a
simple, efficient, and rapid means for freezing
small ice blocks.

Another object is to provide means which may
10 be operated continuously or intermittently for
producing small ice blocks in an efficient manner.

Various other features of the invention are
hereinafter described and claimed in the ap-
pended claims.

15 Further objects and advantages of the pres-
ent invention will be apparent from the fol-
lowing description, reference being had to the
accompanying drawings, wherein a preferred
embodiment of one form of the present inven-
tion is clearly shown.

20 In the drawings:

Fig. 1 is a transverse section through the de-
vice and is taken on line 1—1 of Fig. 2.

Fig. 2 is a longitudinal section taken on line
25 2—2 of Fig. 1.

Fig. 3 is a cross section through the container
belt taken on line 3—3 of Fig. 1.

The illustrations in the drawings are more or
less diagrammatic for the sake of clearness.

30 A large rotating refrigerated drum 10 fixed to
a shaft 11 is suitably mounted upon bearings 12
in a stationary frame 13 of any suitable con-
struction. The metal face 14 of drum 10 has a
large number of recessed cavities 15 therein
35 which preferably are spaced slightly apart to
provide spaces 16 therebetween on the inside of
the drum to permit the circulation of a suitable
refrigerant in spaces 16. (See Fig. 2). Drum
10 has a cylindrical wall 20 therein which pro-
vides a sealed annular refrigerant chamber 21
40 within which a suitable refrigerant may be cir-
culated immediately adjacent the freezing face
14 thereof. In the form shown a suitable re-
frigerant enters chamber 21 through the pas-
sage 22 in one end of shaft 11 and thence
45 through duct 23 to chamber 21. The refriger-
ant leaves chamber 21 through a similar duct
24 and passage 25 at the other end of shaft 11.
Refrigerant is led to and away from passag-
es 22 and 25 through stationary ducts 26 and 27
50 which are connected to the rotating shaft 11
by suitable leak-proof sealing joints 28 and 29.
In the drawings the joints 28 and 29 are shown
as simple packing joints suitable only for the
55 use of cold brine as the refrigerant, however

a compressed and condensed refrigerant such
as sulphur dioxide or other well-known re-
frigerant may be used with this device, in which
event a suitable and well-known type of gas-
tight sealing joint should be used at the con-
nections 28 and 29. It is to be understood that
5 drum 10, shaft 11, ducts 23 and 24, and the
metal parts enclosing chamber 21 all rotate as
a unit hence it will be a simple matter to pro-
vide leak-proof joints at all other points than
10 at the relatively rotating joints 28 and 29. 30
represents a brine circulating pump if cold brine
is used, and a compressor if a compressed re-
frigerant is used, this showing being merely dia-
grammatic. An electric motor 31 drives pump 15
30 at one end of its shaft 32 and drives drum
10 at a suitably slow rate through worm and
wheel gears 33, 34, and 35, 36, as will be readily
understood from the drawings.

A continuous flexible container band or belt
20 50 rides upon and is moved by the rotating drum
10. Belt 50 is preferably molded of soft flexible
rubber or other suitable flexible material and
is provided with a series of ice pockets 51 which
conform in shape to and seat individually within
25 the cavities 15 in the outer face 14 of the drum
10, as clearly illustrated. This provides a very
close thermal relation between the contents of
pockets 51 and the refrigerant within chamber
21 and hence provides rapid heat transfer and
30 consequently rapid freezing of the contents in
container pockets 51. Belt or band 50 also rides
upon the smaller rotatable drum 60 which is
suitably mounted upon bearings in frame 13.
As band or belt 50 passes around drum 60 the
35 flexible bottoms 52 of the ice pockets 51 are
distorted or pressed upwardly by contact with
the face of drum 60 and thus the frozen ice
blocks 53 are loosened from the walls of pockets
51 and are ejected therefrom (see illustration in
40 Fig. 1). Drums 10 and 60 preferably have end
flanges to aid in properly guiding the belt 50
thereon.

A cold water tank 70 is located so that the
lower portion of drum 50 is always submerged
45 under the water level 71 therein. A continuous
flexible water-retainer belt 72 is suitably
mounted upon rollers 73, 74, 75, and 76 so that
it will engage and ride upon the outer face of
flexible belt 50 from point A to point B and so
50 retain the water in the pockets 51 as they
emerge from the water in tank 70 until they
reach an upright position as shown in Fig. 1.
If the freezing action of the device is suffi-
ciently rapid the retainer belt 72 may ride upon
55

- belt 50 only far enough to retain the water in pockets 51 until the water is frozen over and will be thus retained in pockets 51 without aid from belt 72. Belt 72 is preferably of flexible material to which ice does not readily adhere, such as flexible rubber, but if desired it may be flexible sheet metal such as thin sheet copper. Belt 72 is pressed by its tension into contact with the marginal edges 53 (see Fig. 3) of the ice pockets 51 and thus the water is securely retained in said pockets from the point A to the point B on drum 10. At point B belt 72 leaves the belt 50 at a tangent and is thereby easily stripped from its frozen bond with the upper surface of the ice blocks 53 in the pockets 51.

The entire chamber 80, within which is located drums 10 and 60, water tank 70 and retainer belt 72, is enclosed with heat-insulating walls 81 to prevent heat entering from the outside and reducing the freezing efficiency of the device. Chamber 80 is of course cooled by the refrigerant in chamber 21 in drum 10 but not to such an extent that the water in tank 70 will be frozen over solid and interfere with the above described operation of the device. The relation of the cooled drum 10 to the water in tank 70 preferably is such that the water is maintained at or near its freezing point but will not be frozen over to such an extent as to prevent the proper rotation of drum 10 and belt 50 even though the device is idle for a considerable period of time. It will be noted that the circulation of refrigerant in chamber 21 starts and stops when the rotation of drum 10 starts and stops since both are actuated by the motor 31. Hence if the device is run continuously for a long period of time the cooling action of the refrigerant will be correspondingly supplied continuously to provide the proper continuous freezing action. But if the motor 31 is stopped the refrigerant circulation is also stopped and the supply of cold refrigerant remaining in chamber 21 will tend to keep the water in tank 70 cold for a period of time, but the quantity of this remaining cold refrigerant will not be sufficient to freeze over tank 70 and prevent the proper starting of the device at the next operation thereof.

As described above, this device may be operated for the continuous production of frozen ice blocks 53 which are ejected at the drum 60. In the form shown in the drawings, an ice reservoir pan 82 is provided into which the ice blocks 53 fall as they are continuously ejected from the belt 50. The ice may be removed from pan 82 at will. Pan 82 is preferably hinged at 83 so that when the device is stopped, or even when the device is permitted to run, pan 82 may be swung to closed position shown in dotted lines at 82' to conserve the cold temperature in chamber 80. If the device is permitted to run with pan 82 in closed position, the ejected ice blocks 53 will simply fall back into the water tank 70 and so aid in maintaining this water near its freezing temperature and thus prevent waste of refrigeration. When the device has been idle for such length of time that the temperature of the water in tank 70 is too high for proper freezing of ice blocks, the device may be run with pan 82 in closed position until the water in tank 70 is reduced to the proper temperature by the cold water or partially frozen contents of the pockets 51 which are dumped by drum 60 and caused to fall back into tank 70.

75 While the form of embodiment of the present

invention as herein disclosed, constitutes a preferred form, it is to be understood that other forms might be adopted, all coming within the scope of the claims which follow:

What is claimed is as follows:

5 1. An ice-freezing device comprising: an endless flexible belt having container pockets carried thereupon, a refrigerated drum and an ejecting drum upon which said endless belt is mounted, means for filling said pockets with liquid to be frozen, means for chilling said refrigerated drum below freezing temperature, and means for moving said belt around said drums whereby the frozen contents in said pockets are loosened as said pockets pass around said ejecting drum.

10 2. An ice-freezing device comprising: an endless flexible belt having container pockets carried thereupon, a refrigerated drum and an ejecting drum upon which said endless belt is mounted, means for filling said pockets with liquid to be frozen, mean for chilling said refrigerated drum to freezing temperature, and means for moving said belt around said drums, whereby the distortion of said flexible belt as it passes around said ejecting drum facilitates the ejection of the frozen contents from said pockets.

15 3. An ice-freezing device comprising: an endless flexible belt having container pockets carried thereupon, two rotatable drums upon which said endless belt is mounted, means for filling said pockets with liquid to be frozen while said pockets are passing around one of said drums, means for freezing said liquid while in said pockets, and means for moving said belt around 20 said drums whereby the frozen contents in said pockets are loosened as said pockets pass around one of said drums.

25 4. An ice-freezing device comprising: an endless flexible belt having container pockets carried thereupon, two rotatable drums upon which said endless belt is mounted, means for filling said pockets with liquid to be frozen, means for freezing said liquid while said pockets are passing around one of said drums, and means for 30 moving said belt around said drums whereby the frozen contents in said pockets are loosened as said pockets pass around one of said drums.

35 5. An ice-freezing device comprising: an endless flexible belt having container pockets carried thereupon, two rotatable drums upon which said endless belt is mounted, means for filling said pockets with liquid to be frozen, means for freezing said liquid while in said pockets, and means for moving said belt around said drums, 40 said pockets having outwardly projecting bottoms so as to have their bottoms deflected upwardly as they pass around one of said drums whereby the frozen contents therein are loosened.

45 6. An ice-freezing device comprising: an endless flexible belt having container pockets carried thereupon, two rotatable drums upon which said endless belt is mounted, means for filling said pockets with liquid to be frozen, means for 45 freezing said liquid while in said pockets, and means for moving said belt around said drums, said pockets being molded of soft flexible rubber and having outwardly projecting bottom walls whereby said bottom walls are forced inwardly as they pass around one of said drums and thereby loosen the frozen contents from the walls of said pockets.

50 7. An ice-freezing device comprising: an endless flexible belt having container pockets car-

75

ried thereupon, two rotatable drums upon which said endless belt is mounted, means for filling said pockets with liquid to be frozen while said pockets are passing around one of said drums, 5 a second flexible belt means covering said pockets to retain them filled until they reach an upright position on said drum, means for freezing said liquid while in said pockets, and means for moving said belt around said drums whereby the 10 frozen contents in said pockets are loosened as said pockets pass around one of said drums.

8. An ice-freezing device comprising: a refrigerated rotating drum, an endless flexible container belt movable around said drum and carrying a plurality of container pockets and having close heat-conducting relation with the contacting surface of said refrigerated drum, means for filling said pockets with liquid to be frozen, means for retaining the liquid in said pockets until they approach an upright position on said drum, and a guide spaced from said drum and having a curved surface over which said belt and pockets move after the liquid in said pockets is frozen whereby said frozen contents are loosened from the pocket walls.

9. An ice-freezing device comprising: a refrigerated rotating drum, an endless flexible container belt movable around said drum and carrying a plurality of container pockets and having close heat-conducting relation with the contacting surface of said refrigerated drum, means for filling said pockets with liquid to be frozen, a flexible belt means covering said pockets to retain the liquid therein until they approach an upright position, and a guide having a curved surface over which said container belt moves after the contents of said pockets are frozen whereby said contents are loosened.

10. An ice-freezing device comprising: a refrigerated rotating drum, an endless flexible container belt movable around said drum and carrying a plurality of container pockets and having close heat-conducting relation with the contacting surface of said refrigerated drum, means for filling said pockets with liquid to be frozen, and means for retaining the liquid in said pockets until frozen by said refrigerated drum.

11. An ice-freezing device comprising: a refrigerated rotating drum, an endless flexible container belt movable around said drum and carrying a plurality of container pockets and having close heat-conducting relation with the contacting surface of said refrigerated drum, a water reservoir positioned so as to submerge the bottom portion of said drum whereby to fill the container pockets as they pass under the water level, means for retaining the water in said pockets until they approach an upright position or until sufficiently frozen, and means for ejecting the frozen contents from said pockets.

12. An ice-freezing device comprising: an endless flexible belt having container pockets carried thereupon, two rotatable drums upon which said endless belt is mounted, means for filling said pockets with liquid to be frozen while said pockets are passing around one of said drums, means for freezing said liquid while in said pockets, and means for ejecting the frozen contents from said pockets.

13. In a device of the character described, an insulated casing containing a belt having a series of pockets formed integral therewith, means including a tank within said casing for filling said pockets with precooled liquid, refrigerating means for freezing liquid in said pockets into ice cubes, and means partly within said casing for delivering ice cubes outside of the casing.

14. In apparatus of the character described, in combination, a continuously revoluble cylinder, an endless flexible member partially encircling said cylinder and having pocket-like cavities therein to receive a liquid and within which the liquid is frozen, means for causing said flexible member to travel away from said cylinder, and means for removing the frozen liquid from said cavities while the flexible member is in motion.

15. An ice freezing device comprising, an endless belt having container pockets carried thereupon, a rotatable member upon which said endless belt is mounted, means for filling said pockets with liquid to be frozen while said pockets are passing around said member, means for freezing said liquid while in said pockets, and a portion of said belt extending outwardly from said rotatable member and engaging a means for ejecting the frozen contents from said pockets.

16. An ice freezing device comprising, an endless belt having container pockets carried thereupon, a rotatable member upon which said endless belt is mounted, means for filling said pockets with liquid to be frozen while said pockets are passing around said member, means for freezing said liquid while in said pockets, at least a portion of said pockets being flexible to permit deformation thereof, and a portion of said belt extending outwardly from said rotatable member and engaging a means which deforms the flexible portion of said pockets to cause the frozen contents thereof to be ejected therefrom.

17. An apparatus for making ice blocks comprising in combination, a water tank, a drum journaled to revolve in a body of water in said tank, means for imparting an ice forming temperature to the periphery of said drum, a pulley member spaced from said drum, an endless band of freezing containers trained over said drum and pulley member, said containers having their closed ends traveling in contact with the periphery of said drum, and means for driving said drum and band.

18. An apparatus for making ice blocks comprising in combination, a water tank, a drum journaled to revolve in a body of water in said tank, means for imparting an ice forming temperature to the periphery of said drum, a pulley member spaced from said drum, an endless band of flexible walled cup-shaped freezing containers trained over said drum and pulley member, said containers having their closed ends traveling in contact with the periphery of said drum, means for driving said drum and band, and said pulley member flexing the closed ends of said containers as and when same travel thereover.
